CASH REGISTER

Application filed December 19, 1928. Serial No. 327,092.

This invention relates to registers and like machines and has more particular reference to the totalizing mechanisms for such machines.

5 The invention, in its preferred form, is applicable to machines of the type disclosed in Letters Patent of the United States, No. 1,242,170, issued October 9, 1917, to F. L. Fuller, and No. 1,619,796, issued March 1, 10 1927 to B. M. Shipley, and in the applications for Letters Patent of the United States, Serial Nos. 608,281 and 687,305, filed December 21, 1922 and January 19, 1924, respectively, by B. M. Shipley.

15 In the manufacture of the above-mentioned class of machines, it is the usual practice to standardize such machines as to capacity. That is, the totalizer or totalizers includes a predetermined number of denominational 20 wheels, for instance, six, in which case the maximum amount which could be accumulated on such totalizer would be \$9,999.99. The totalizers of other standardized types of machines may have a larger or smaller number of denominational wheels, but in each instance, a predetermined number. In any case, it is frequently desirable to increase the accumulating capacity of the totalizer without 25 increasing the physical dimensions of the machine which precludes the assembly of additional denominational wheels on the totalizer shaft.

30 In the type of machine to which this invention relates, such a procedure would entail a decided increase in the width of the machine. It is a well known fact that, once the manufacture of a machine of this type is standardized, any departure from the established process of manufacture, such as, for 35 instance, widening the machine, requires changes in the main frames, bases, cabinets, etc., which is extremely costly, and production is curtailed by the installation of such changes.

40 It is also desirable at times to increase the capacity of the keyboard of this type of machine. It is customary to provide one or more differential units and corresponding overflow totalizer wheels in excess of the number of 45 rows or banks of amount keys, the additional

differentials serving as carrying mechanisms between the totalizer wheels corresponding with the individual rows or banks of keys, and the overflow totalizer wheels for which no corresponding banks of keys are provided.

55 To increase the keyboard capacity of such machines, it is only necessary to assemble a bank of amount keys in the machine to cooperate with each of the excess or overflow differential units. If this is done, however, 60 there remains no mechanism to take care of amounts added into or accumulated on the totalizer in excess of its capacity.

65 It is, therefore, an object of this invention to provide a simple and novel means in a machine of the type disclosed in the patents mentioned above, whereby the capacity of the totalizer may be increased without materially increasing the cost of production, or delaying such production.

70 Another object is to provide a novel step-by-step counter to count the number of times the capacity of the main totalizer is exceeded.

75 Another object is to provide a novel overflow counter whereby additional rows of keys may be employed to control the totalizer actuating mechanism which otherwise serves only as a carrying device.

80 With these and incidental objects in view, the invention consists of certain novel features of construction and combinations of parts, the essential elements of which are set forth in appended claims and a preferred form of embodiment of which is hereinafter described with reference to the drawings 85 which accompany and form a part of this specification.

In the drawings:

90 Fig. 1 is a transverse sectional view through a machine of the type above referred to, showing a bank of amount keys, a differential mechanism operated under control thereof, and three lines of totalizers actuated by the differential mechanism to accumulate amounts set up on the keyboard.

95 Fig. 2 is a detail side view of the mechanism for engaging and disengaging the back totalizer with the actuators.

100 Fig. 3 is an enlarged top plan view of the auxiliary or overflow totalizer.

Fig. 4 is an enlarged detail view of the auxiliary or overflow totalizer.

Fig. 5 is a view in rear elevation of the back totalizer and the mechanism for tripping the actuating means for the auxiliary totalizer.

Fig. 6 is a detail side view of the device for adding a single unit in the overflow totalizer when the regular totalizer wheel of highest denominational order exceeds its capacity.

Fig. 7 shows the auxiliary totalizer operating means in normal position.

Fig. 8 is a detail view of the auxiliary totalizer operating device in the position assumed when the regular totalizer is engaged with its actuators, the latch having been tripped by the high tooth passing from its "nine" to its "zero" position.

Fig. 9 is a view of the same mechanism as shown in Fig. 8, after the totalizer has been disengaged and the actuating device for the auxiliary totalizer has been tripped.

The present invention utilizes a well-known step-by-step counter substantially of the type shown in Letters Patent of the United States, No. 1,735,062, granted to B. M. Shipley, the present inventor.

It is also customary to provide machines of the type to which this invention is applied, with a plurality of groups or lines of totalizers.

The purpose of this invention, that is, the addition of a single unit into a step-by-step counter every time the capacity of a particular one of a plurality of totalizers exceeds its capacity, is accomplished by a normally ineffective actuating means for the counter, which actuating means is rendered effective by the tripping of a latch by the totalizer wheel of highest denominational order as it turns from its "9" to its "0" position, or in other words, when said wheel exceeds its capacity.

Obviously, the mechanism might be duplicated for each line or group of totalizers, so that with three step-by-step counters, a particular totalizer in each line would have a corresponding exceeded-capacity counter.

The totalizer wheel of highest denominational order in the machine of the type disclosed in the above mentioned patents and applications, is usually actuated by a differential mechanism exactly like that associated with the lower order wheels. However, the corresponding differential actuator was not controlled by a row of depressible keys, but merely acted as a transfer or carry-over device from the next lower order wheel, and in total and sub-total printing operations.

For convenience of illustration, and to better disclose the usefulness of the present invention, a bank or row of keys 30 (Fig. 1) is shown in connection with the differential mechanism associated with the highest order totalizer wheel in the machine.

The keys 30 and the differential actuator mechanism associated therewith are old in this type of machine, as indicated in the patents and applications mentioned above. However, a brief description of this structure and its operation will be included in this application.

Keyboard

The keyboard of the machine comprises a plurality of banks or rows of keys 30 (Fig. 1) slidably mounted in denominational key frames 31 supported on cross rods 32 and 33 extending between the side frames 34 and 44 of the machine, a fragment of the side frame 44 appearing in Fig. 5. Upper and lower swinging arms 37 and 38 pivotally support a detent bar 36 extending along each row of keys 30, the detent bar carrying a laterally projecting stud 35 adjacent each key. A spring 39 attached to a bell crank 41 fast on a short shaft 42 journaled in a foot extending from the lower end of the key frame 31, presses a roll 40 on one arm of the bell crank lever against the lower supporting arm 38 of the detent bar 36 to hold the latter in its normal position. When a key 30 is depressed, a locking shoulder thereon crowds past the corresponding laterally extending stud 35 on the spring-pressed detent bar 36 until it escapes 95 the stud, whereupon the stud 35 snaps over the shoulder to retain the key depressed.

Displacement of the detent bar during the depression of a key 30 rocks the short shaft 42 which carries a zero stop 43 to remove the zero stop from the path of an arm 49 on a differentially positioned actuator 50, so that upon operation of the machine, the actuator may be variously positioned under the control of whichever of its keys has been depressed.

Mechanism, not shown herein, releases the depressed key 30 near the end of each operation of the machine, and a spring (not shown) restores said depressed key to its normal outward position, as is fully set forth in the above-mentioned patents and applications. After the key 30 is released, the spring 39 rocks the bell crank 41 and short shaft 42 clockwise to raise the detent bar 36 to its normal position, and return the zero stop 43 to position to arrest the travel of the differential elements now to be described.

Differential mechanism

In order to add the amounts set up on the amount keys 30 into the selected totalizer or totalizers provided in the machine, the keys 30 control the differential movement of the totalizer actuators 50. A latch 51 normally connects each actuator 50 to its invariably movable drive segment 52. A pair of cams 53 fast on a drive shaft 54, journaled in the side frames 34 and 44, operates a drive lever 55 connected by a link 56 to the drive segment 52.

to rock said segment first clockwise and then counter-clockwise to normal position.

The drive segment 52 on its clockwise movement carries the totalizer actuator 50 therewith by the latch 51 until the latter strikes the inner end of the depressed key which effects the disconnection of the latch 51 from the segment 52 or, if no key in the particular bank or row is depressed, the zero stop 43 arrests the 10 totalizer actuator 50 in its zero position in a manner well known in the art.

At this point in the operation of the machine, mechanism to be described later, operates to engage the adding wheels of the selected totalizer or totalizers with their respective actuators 50, after which each pair of cams 53 rocks its drive segment 52 counter-clockwise back to normal position. The drive segment 52 on its counter-clockwise travel 20 picks up its actuator 50 and restores it to home position in a well known manner, as is fully disclosed in any of the above-mentioned patents or applications.

Totalizers

25 A plurality of totalizers is provided in the machine, assembled on three separate lines, A, B, and C. However, as this invention concerns but one totalizer line, and only one totalizer on that line, and inasmuch as the totalizer selecting and engaging mechanisms, and other features, are fully disclosed in the above-mentioned patents and applications for Letters Patent, it is unnecessary to include 35 a detailed description of all of said totalizers and totalizer lines in this application. Therefore, the description of the totalizer will be confined to the single line located generally at the back of or behind the actuators, the other 40 totalizers provided in the machine being of the same type.

The back totalizer comprises a plurality of denominational totalizer wheels 70 (Fig. 5) and 71 rotatably mounted on a tube 72 and 45 spaced apart by spacing collars 73. Brackets 74 and 75 journaled on a shaft 76, support the tube 72 between them. Collars 77 fast on the shaft 76 prevent longitudinal movement of the brackets 74 and 75 along the 50 shaft, and maintain the totalizer wheels 70 and 71 in alignment with their respective actuators 50. Anti-friction rollers 79 (Fig. 2) on the ends of the shaft 76 cooperate with 55 guide slots 80 (Figs. 7 to 9) and 81 (Fig. 2) in cam plates 82 and 83 (Fig. 5) secured to the inner faces of the side frames 34 and 44, respectively, to guide the totalizer as it is moved into and out of engagement with its 60 actuators.

65 The mechanism for engaging and disengaging the totalizer relatively to its actuators includes a pair of cams 84 and 85 (Fig. 2) fast on the drive shaft 54, adapted to rock a lever 90 pivotally mounted on a suitably supported stud 91, first clockwise and then

counter-clockwise to normal. A rocking pitman 92 pivoted at one end to one arm of the lever 90 and slotted at its opposite end to embrace a supporting stud 93, is shifted by the lever 90. The pitman has a large opening to accommodate a stud 95 during the several movements of the pitman. One of the two opposed forks on the pitman releasably engages a stud 96 on a substantially circular totalizer engaging and disengaging spider 94 centrally pivoted on the stud 95 projecting from the side frame 44.

70 There are as many hooks 69 extending radially from the totalizer engaging and disengaging spider as there are lines or groups of totalizers, one only being shown in Fig. 2, each hook adapted to catch over a stud 97 carried by a link 98 pivotally attached to an arm 99 fast on the bracket-supporting shaft 76. The arm 99 also carries a roll 100 adapted to traverse a cam slot 101 formed in the adjacent fixed plate 83. A roller 102 (Figs. 6, 7 and 8) on an arm 103 fast on the supporting shaft 76 near the opposite end of the shaft, as viewed in Fig. 5, traverses a cam slot 104 in the cam plate 82.

75 When the cams 84 and 85 on drive shaft 54 rock the lever 90 clockwise, the lever draws the pitman 92 toward the right and rocks the totalizer engaging and disengaging spider 94 clockwise. The hook 69 of the spider normally engages the stud 97 in the link 98 pivoted to the arm 99, so that the spider, on its clockwise movement, draws the link 98 toward the left and rocks the arms 99 and 103 and the shaft 76 counter-clockwise, to cause the anti-friction rollers 100 and 102 on the arms 99 and 103, to traverse the cam slots 101 and 104 in the cam plates 83 and 82. The cam slots guide the shaft 76, brackets 74 and 75, and the tubes 72, to engage the totalizer wheels 70 and 71 with their respective actuators 50. At the proper time, cams 84 and 85 operate through the lever 90 and pitman 92 to rock the spider 94 counter-clockwise and rock arms 99 and 104 clockwise to thereby disengage the totalizer wheels from their actuators.

80 All of the above described structure is old and only forms a part of the present invention when combined with the novel mechanism now to be described.

Exceeded capacity counter

85 The invention finds its greatest utility when applied to machines of reduced capacity. The usual practice in the cash register art is to provide denominational rows or banks of keys to control corresponding actuators in all but the higher orders, utilizing the higher order actuators to effect transfers into the overflow totalizer wheel or wheels. In certain models of cash registers, this 90 practice results in limiting the number of de-

115

120

125

130

nominational rows of keys to four, it being customary to provide at least two overflow totalizer wheels. The accumulating capacity of the totalizers is \$9,999.99, whereas the largest capacity of the keyboard is but \$99.99.

It is sometimes desirable to increase the registering capacity of the machine without increasing the size thereof, and to do so it becomes necessary to provide additional overflow totalizer wheels, that is, totalizer or counter wheels which will accumulate "1" each time the wheel of highest order of that section of the totalizer which is directly driven under control of the keys passes or exceeds its capacity, thereby extending the accumulating capacity of said totalizer.

Due to the narrowness of the machine, it is impracticable to locate these exceeded capacity wheels on the same axis with the directly driven totalizer wheels 70 and 71, and therefore, mechanism is provided under the control of the directly-driven totalizer wheel of highest order to actuate a step-by-step counter.

This counter, an enlarged detail view of which is shown in Figs. 3 and 4, comprises a plurality of number wheels 110 rotatably mounted on a rod 111 extending between parallel side plates 112 and 113 secured to a frame 114 supported on the cross rods 32 and 33 (Fig. 6) alongside the key frames 31. A spring-pressed tined pawl 115, (Fig. 4), pivoted on a cross bar 116 extending between the arms 117 and 118 of a yoke 119, rocking on the rod 111, cooperates with ratchets 120, one secured to the side of each of the number wheels 110, to advance the wheels step-by-step under control of the highest order totalizer wheel 71 (Fig. 5). The mechanism for rocking the yoke 119 is actuated each time the back totalizer is moved into and out of engagement with its actuators 50, but is normally ineffective to rock said bail. When the highest order wheel 71 turns from its "9" position to its "0" position, the actuating mechanism for the auxiliary counter is rendered effective to advance the units counter one step, as follows.

It will be remembered that the supporting shaft 76 is rocked first counter-clockwise to engage the totalizer with its actuators, and then clockwise to disengage the totalizers from the actuators at each operation of the machine. An arm 126 (Figs. 5-9) fast on the shaft 76 carries a stud 125 which projects through a cam slot 127 in one arm 128 of a bell crank pivoted on a shaft 129 journaled in the side frames 34 and 44. The other arm 130 of the bell crank carries a stud 131 projecting into an angular opening 132 in an enlarged end of a link 133. The other end of the link 133 is pivoted on one arm 134 (Fig. 6) of a lever pivoted on a shaft 135 journaled in the side frames 34

and 44 of the machine. A link 136 connects the other arm 137 of this lever to an arm 138 (Fig. 4), of a counter-operating lever pivoted on the rod 111. The other arm 139 of the counter operating lever is bifurcated and embraces the rod 116 on which rocks the tined counter-operating pawl 115.

When the drive mechanism illustrated in Fig. 2 rocks the supporting shaft 76 and the arm 126 counter-clockwise, the stud 125 on the arm 126 swings around with the shaft 76 and, at the same time, the shaft 76, arm 126, and stud 125 are moved bodily toward the center of the machine to engage the totalizer wheels with their actuators 50, as described above. This movement of the stud 125 rocks the bell crank 128-130 counter-clockwise, but the stud 131 on the arm 130 idly traverses the horizontal section of the opening 132 in the link 133, and the link is normally held in the position shown in Figs. 6 and 7 by the contact of a stud 145 in said link with a shoulder 146 of a latch 147 pivotally supported on the shaft 129. A spring 148 normally returns these parts to and retains them in the positions in which they are shown in Figs. 6 and 7. So long as the shoulder 146 remains under the stud 145, the link 133 is restrained and the stud 131 rocks idly in the opening 132. A trip arm 149 fast to the latch 147, but laterally spaced therefrom by a hub 150, (Fig. 5), lies in the path of a tripping tooth 152 carried by a wheel 151 secured to the totalizer wheel 71. The tripping tooth 152 is offset radially from the wheel 71 one-half tooth space, and when the wheel 71 is in its "9" position, said tripping tooth 152 occupies a position as shown in full lines in Fig. 7, the parts being in their positions with the totalizer in its normal disengaged position.

When the totalizer is moved into engagement with the actuators 50 while the tripping tooth 152 lies in its "9" position, said tooth assumes a position shown in Fig. 7 by dot-and-dash lines. When the totalizer wheel 71 turns clockwise to register a further amount onto said wheel, the tripping tooth 152 travels clockwise from the position indicated by dot-and-dash lines in Fig. 7 to the full line position shown in Fig. 8, wiping past the nose of the tripping arm 149 to rock this arm and the latch 147 clockwise and withdrawing the shoulder 146 of the latch from beneath the stud 145 on the spring-drawn link 133.

Link 98 (Fig. 2) in drawing the totalizer into engagement with its actuators, rocks the arms 99 and 103 (see also Fig. 7) to turn the supporting shaft 76 sliding along the radial guide slots 80 and 81. The shaft 76 rocks the arm 126 and its stud 125 (Figs. 6-9) from the position shown in Figs. 6 and 7 to the position shown in Fig. 8, the stud traversing the cam slot 127 in the arm 128 of

the actuating bell crank to rock arm 130 of the bell crank slightly counter-clockwise to position the stud 131 opposite the offset part of the opening 132 in the link 133. Therefore, when the tripping tooth 152 rocks the tripping arm 149 and latch 147 to disengage the shoulder 146 from the stud 145, the spring 148 swings the link 133 clockwise on its pivot on the arm 134 and fits the offset part of the opening 132 over the stud 131. With the parts in such positions, when the totalizer engaging mechanism (Fig. 2) operates to disengage the totalizer from the actuators, it rocks the shaft 76, arm 126 and stud 125 clockwise from the position shown in Fig. 8 to that shown in Fig. 9.

This movement of the stud 125 rocks the bell crank 128-130 clockwise to its normal position and, since the link 133 is now connected to the stud 131 by reason of the offset of the opening 132 falling over the stud, said link is drawn toward the right, and through the lever 134-137, link 136 and lever 138-139, (Fig. 4) rocks clockwise the arms 117 and 118 carrying the cross bar 116 to actuate the tined pawl 115 to advance the counter wheel 110 of lowest order one step.

Spring-pressed retaining pawls 153 (Figs. 3 and 4) cooperate with ratchets 120 fast with the respective number wheels 110 to prevent retrograde movement of the number wheels. These pawls are pivoted on a rod 154 extending between the side plate 112 and a small bracket 155 supported on the short rod 111 and secured to the side plate 113 by a stud 156. A spring 157 coiled about the rod 154 adjacent each retaining pawl 153 serves to hold the pawls against the ratchets 120. Each spring is tensioned between its pawl and a bar 158 conveniently bent at right angles from the side plate 112 and having its free end supported in a notch provided for that purpose in the side plate 113.

The link 133 (Fig. 6) remains in the position in which it is shown in Fig. 8 at the end of an operation on which said link has been actuated to operate the auxiliary totalizer. Mechanism is operated early in the next succeeding operation to restore the link 133 to its normal untripped position.

Shortly after the beginning of an operation, a pair of cams 165 and 166 (Fig. 6) fast on the drive shaft 54, rocks a forked arm 167 counter-clockwise, the arm being pivoted on a stud 168 projecting laterally from the side frame 34. A link 169 connects the forked arm 167 with an arm 170 fast on an indicator aligner shaft 171 journaled in the side frames 34 and 44, to rock the aligner shaft first clockwise and then counter-clockwise to normal, and with it an indicator locking bell crank 174 likewise fast on the shaft. A link 173 pivoted at one end to one arm of the indicator locking bell crank 174 is slotted to surround a stud 175 projecting laterally from the

actuating link 133 for the auxiliary totalizer.

The slot in the link 173 permits the actuating link 133 to shift in clockwise direction to fit the offset notch of its opening 132 over the stud 131 of the driving arm 130 and thus couple the driving arm and actuating link 133 preliminary to an operation of the auxiliary totalizer, as heretofore explained.

In such positions of the parts, the stud 175 on the actuating link 133 occupies a position near the bottom of the slot 172 in the link 173, so that when, shortly after the beginning of the next succeeding operation, the cams 165 and 166 rock the aligner shaft 171 and locking bell crank 174 clockwise, the link 173 will be drawn upwardly to lift the actuating link 133 until its offset notch of the opening 132 clears the stud 131 of the driving arm 130, and by the same movement the latching stud 145 on the actuating link 133 is caused to clear the shoulder 146 on the latch 147, whereupon spring 148 rocks the latch 147 counter-clockwise to position the shoulder 146 under the stud 145. Removal of the offset notch of opening 132 from the stud 131 enables a spring 176 attached to the arm 137 to rock the bell crank 134-137 counter-clockwise to restore the actuating link 133 to its normal position and to lower the link 136, thereby rocking the lever 138-139 (Fig. 4) counter-clockwise to retract the tined actuating pawl 115 one step preparatory to another operation.

A brief description of the operation of the invention will now be given.

Assuming that all of the main totalizer wheels 70 and 71 (Figs. 1 and 5) are in their "9" positions, and that an amount is about to be added onto this totalizer. When the totalizer engaging mechanism (Fig. 2) rocks the shaft 76 counter-clockwise, as viewed in Fig. 6 to engage the totalizer wheels 70 and 71 with their actuators 50, the arm 126, by its stud 125 operating in cam slot 127, rocks the bell crank 128-130 counter-clockwise to position the stud 131 in the path of the offset notch of the opening 132 in the actuating link 133. The main totalizer is now in engagement with the actuators 50, which are then rocked counter-clockwise, as viewed in Fig. 1, to turn the totalizer wheels 70 and 71 clockwise to accumulate on the totalizer the amount corresponding to the value of the depressed keys. As the totalizer wheel 71, that is the highest order totalizer wheel, rotates in a clockwise direction from its "9" position, the tripping wheel 151 in turning therewith, carries the high tooth or tripping tooth 152 past the nose of the tripping arm 149, rocking this arm and the latch 147 to displace the shoulder 146 from the path of the stud 145, whereupon the spring 148 immediately swings the link 133 clockwise, pivoting at its upper end to fit the offset notch of the opening 132 over the stud 131. Now when the totalizer engaging and disengaging mech-

anism illustrated in Fig. 2 rocks the shaft 76 clockwise to disengage the main totalizer from the actuators 50, the arm 126 causes its stud 125 to retrace its path along the cam slot 127 in the arm 128, thereby rocking the bell crank 128—130 clockwise and, as the offset notch of the opening 132 in link 115 is now fitted over stud 131 on the arm 130, the bell crank 128—130 draws the actuating link 133 towards the right to rock the bell crank lever 134—137 clockwise, and through the link 136, rocks the counter operating lever 138—139 (Fig. 4) clockwise to advance the counter wheel 110 of lowest order one step.

15 As long as the main totalizer does not exceed its capacity, the tripping tooth 152 does not strike the nose of arm 149 to displace the shoulder 146, which continues to hold the actuating link 133 in its disconnected position relatively to the arm 130, and the arm 130 merely carries its stud 131 idly back and forth in the horizontal opening 132 during each operation of the machine.

20 While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

25 What I claim as new, is:—

1. In a machine of the class described; the combination with a totalizer, actuators 35 for said totalizer; and means to engage and disengage the totalizer relatively to the actuators; of a step-by-step counter; normally ineffective counter-actuating means operable by the totalizer engaging and disengaging means as said totalizer is disengaged from the actuators to actuate the step-by-step counter; and means under the control of the highest order totalizer wheel to render said actuating means effective.

40 2. In a machine of the class described; the combination with a main totalizer; actuators therefor; and means to engage and disengage the totalizer relatively to the actuators; of an auxiliary counter; a train of counter-actuating means, said train being operated by the totalizer engaging and disengaging means, and normally uncoupled therefrom; means to retain uncoupled the train of counter-actuating means; and means operated by the totalizer wheel of highest order to disable the retaining means and enable the coupling of the train of counter-actuating means with the totalizer engaging and disengaging means, and its effective operation by the totalizer engaging and disengaging means as the totalizers are disengaged from their actuators.

45 3. In a machine of the class described, the combination with a main totalizer; actuators therefor; and means to engage and

disengage the totalizer relatively to the actuators; of an auxiliary counter; a train of counter-actuating means, said train being operable by the totalizer engaging and disengaging means; and comprising a drive member operable in one direction as the totalizer is engaged and in the opposite direction as the totalizer is disengaged; and an actuating link normally uncoupled from the drive member; means to retain the drive member and actuating link uncoupled; and means operated by the totalizer wheel of highest order to disable the retaining means and enable the coupling of the drive member and the actuating link to effect the actuation of the auxiliary counter.

50 4. In a machine of the class described; the combination with a main operating mechanism; a main totalizer comprising a plurality of totalizing elements; actuators for the elements; and means to engage and disengage the elements relatively to the actuators; of a step-by-step counter; an actuating link to operate the counter, said link having an effective position and an ineffective position; a drive member for the link; means to normally retain the actuating link in its ineffective position relatively to the drive member; means, under the control of the totalizer element of highest order, to disable the means which normally retains the link ineffective, to enable the drive member to operate the link and the step-by-step counter.

55 5. In a machine of the class described; the combination with a plurality of totalizer elements; actuators therefor; and means to engage and disengage the totalizer elements relatively to their actuators; of a counter; a supporting shaft turned by the engaging and disengaging means incident to engaging and disengaging the totalizer elements relatively to their actuators; a shiftable drive member operated by the shaft; a link intermediate the drive member and the counter, and normally uncoupled from the drive member; means to retain said link in its uncoupled position; means operated by the totalizer element of highest order as said element exceeds its capacity to displace the retaining means and release the link; means to couple the link and the drive member to enable the latter to operate the counter; and means operable incident to the engagement of the totalizer elements with their actuators on the succeeding operation of the machine, to uncouple the link and its drive member to enable the retaining means to become effective.

60 6. In a machine of the class described; the combination with a plurality of totalizer elements; means to actuate said elements; and means to engage and disengage said elements relatively to the actuating means; of a counter; a supporting shaft actuated by the engaging means incident to engaging and disengaging the totalizer elements relatively to the

actuators; a drive member operated by said shaft; an actuating link between the drive member and the counter and normally ineffective relatively to the drive member; means to normally retain the link in its ineffective position; means under the control of the highest order totalizer wheel to disable the retaining means; and a spring to move the link to its effective position.

7. In a machine of the class described; the combination with a plurality of totalizer elements; means to actuate said elements; and means to engage and disengage said elements relatively to the actuating means; of a counter; a shaft having an arm, and actuated by the engaging and disengaging means incident to engaging and disengaging the totalizer elements relatively to the actuators; a drive member having a cam race traversed by the arm; an actuating link interposed between the drive member and the counter; means to automatically uncouple the link relatively to the drive member; means to normally latch the link in its ineffective position; and means under the control of the highest order totalizer wheel to displace the latch means.

In testimony whereof I affix my signature.
BERNIS M. SHIPLEY.
